TOBACCO PIPE

Benjamin H. Tyler, Portland, Oreg.

Application September 13, 1938, Serial No. 229,718

1 Claim. (Cl. 131—215)

A dry smoke is the desire of all pipe smokers. To attain this result the flow of saliva into the bowl of the pipe must be prevented; in other words, the tobacco must not become moistened by saliva. When tobacco becomes thus moistened in the bowl of the pipe, it cannot be entirely consumed, and a wastage of tobacco results. It is further maintained that a dry smoke carries less nicotine to the smoker and therefore renders excessive smoking less injurious.

It is further essential that provision be made in pipe construction for easily cleaning the smoke-channels of the pipe, since frequent cleaning is necessary. It is further desirable that pipes ordinarily used be inexpensive. Many expediences have been resorted to in pipe construction in order to provide a dry smoke. Saliva retainers have been employed; also the smoke channel has been so arranged as not to lead to the bowl directly. Nevertheless, in the tobacco pipe constructions, as known to me, the objectives of my invention have not previously been obtained. The construction excluding the flow of saliva into the bowl of the pipe rendered the pipe more or less expensive; and, furthermore, was of such a nature as to render cleaning of the pipe more or less difficult.

The object of my invention is to prevent saliva entering the bowl of the pipe in order to assure a dry smoke, and also to prevent the collecting of saliva at any place in the pipe, in order to prevent the pipe from becoming offensive in odor and unclean, as results from permitting the collecting and holding within the pipe of saliva saturated with tobacco fumes. The accomplishment of both of these objectives is important, and, therefore, unless the pipe is so constructed as to accomplish both objectives, it will soon become offensive. Furthermore, the construction of the pipe should be such that it may be easily thoroughly cleaned.

I attain my object in a tobacco pipe comprising a bowl-piece having vertically disposed, converging branch smoke ducts of equal bore, the juncture of said ducts connected by a cavity closed by a removable plug, in combination with a stem having a smoke duct of the same bore as such branch ducts, the stem secured to the bowl by means effecting a direct and close contact between the bore of the stem and the downwardly extending branch of said smoke duct of the bowl, and so as to prevent any escape and collecting of saliva within the pipe.

The specific manner in which I carry out my invention is hereinafter described with reference to the accompanying drawing, in which

Fig. 1 is a side elevation of a pipe embodying my improvement;

Fig. 2 is a corresponding partial plan or top view;

Fig. 3 is a central longitudinal section of my pipe; and

Fig. 4 is a similar partial section with the stem of the pipe removed, and illustrating further the mode of cleaning the smoke channels of the bowl-portion of my pipe.

The bowl-piece *a* is provided with a central tobacco holding chamber *b* and has a neck *c* in which is inserted the pipe stem *d*. The pipe stem has a smoke passageway or channel *e* and the neck *c* of the bowl-piece *a* has a smoke channel *f*. One side of the bowl-piece is made thicker as at *a'* and this portion is provided with a smoke channel consisting of two straight branches *g* and *h*; these branches being preferably arranged in a vertical plane; the channel branch *g* extending upward from the bottom of the tobacco holding chamber *b* of the bowl, and the smoke channel branch *h* extending downward from the top of branch *g* and connecting with the smoke channel *f* of the neck *c* of the bowl-piece. The apices of the smoke channel branches *g* and *h* extend into and are connected by cavity *i* in the top of the portion *a'* of the bowl-piece. The cavity *i* is preferably closed by a short closure plug *j* adapted to leave a space under it in the cavity *i*, which connects the smoke channel branches *g* and *h*. These branches being straight are easily drilled thru the thicker wall *a'* of the bowl-piece.

The channel branches *g* and *h* are preferably so made that their longitudinal axes intersect and extend thru the cavity *i*. Thus by removing the plug *j* stiff pipe cleaning implements, indicated by *k* in Fig. 4, may be inserted in the channel branches *g* and *h* for cleaning the same. *k* in Fig. 4 also indicates a pipe cleaning implement.

Without limiting myself to the exact details of construction above described of my invention, I claim:

A tobacco pipe comprising a bowl having vertically disposed upwardly converging straight smoke ducts of equal bore, the juncture of said ducts being connected by a cavity, a removable plug closing the cavity, one of said ducts leading to the bottom of the bowl of the pipe, and a removable stem having a smoke duct of the same bore as said upward converging ducts, the stem being secured to the bowl by means effecting a direct and close contact, between the duct of the stem and one of the upwardly converging ducts of the bowl, so as to prevent any escape and collecting of saliva within the pipe.

BENJAMIN H. TYLER.
